United States Patent Office

Des. 183,877
Patented Nov. 11, 1958

183,877

BOTTLE PACK

Urban H. Despres, Clinton, Maine, assignor to Keyes
Fibre Company, Portland, Maine, a corporation of Maine

Application March 27, 1956, Serial No. 40,800

Term of patent 14 years

(Cl. D58—6)

Fig. 2

Fig. 1

Fig. 3

Fig. 1 is a side elevational view of a bottle pack embodying my new design; the bottle pack being shown in closed position;

Fig. 2 is a top plan view of the bottle pack in closed position; and

Fig. 3 is a top plan view of the bottle pack in open position.

The side, not shown, is the same as the side shown.

What is claimed:

The ornamental design for a bottle pack, as shown and described.
